(57) **CLAIM**

We claim the ornamental design for a housing for a fan motor, as shown and described.

DESCRIPTION

FIG. 1 is a front side elevation view of a housing for a fan motor;

FIG. 2 is a rear side elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross sectional view as taken along 7-7 line in FIG. 1;

FIG. 8 is a cross sectional view as taken along 8-8 line in FIG. 1;

FIG. 9 is a cross sectional view as taken along 9-9 line in FIG. 1;

FIG. 10 is a cross sectional view as taken along 10-10 line in FIG. 1; and,

FIG. 11 is a perspective view thereof.

The broken-line disclosure in the views is understood to represent portions of the article in which the claimed design is embodied, but which form no part of the claimed design. Where a broken-line abuts a claimed surface, that broken line is understood to represent an unclaimed boundary between claimed and unclaimed surfaces.
